FIG. 3.

FIG. 4.

UNITED STATES PATENT OFFICE.

CARL E. LUNDBERG, OF SPOKANE, WASHINGTON.

STAND FOR CALENDAR-PADS.

1,283,238.

Specification of Letters Patent.

Patented Oct. 29, 1918.

Application filed February 20, 1917. Serial No. 149,899.

To all whom it may concern:

Be it known that I, CARL E. LUNDBERG, a citizen of the United States, residing at Spokane, in the county of Spokane and State 5 of Washington, have invented certain new and useful Improvements in Stands for Calendar-Pads, of which the following is a specification.

This invention relates to desk stands and 10 more particularly to stands designed for the support of calendar and memorandum pads comprising a number of perforated leaves, and it is one aim of the invention to provide a stand of this class which will be neat 15 in appearance, compact in form, and which will be so constructed that while adapted for firm support upon a desk will not be liable to mar the finish thereof.

Another aim of the invention is to so 20 construct the stand that the memorandum or calendar pad may be readily removed therefrom and a new one substituted therefor and without the necessity of performing the tedious operation of separately threading 25 the leaves on to the filing member of the stand.

Another aim of the invention is to so construct the stand that the backing leaves for the pad will serve to prevent disarrangement 30 of the members comprising the stand which would be liable to release the leaves of the pad.

In the accompanying drawings:

Figure 1 is a perspective view illustrating 35 the device embodying the present invention in use;

Fig. 2 is a vertical front to rear sectional view through the stand and the pad supported thereby;

Fig. 3 is a bottom plan view of the stand and pad;

Fig. 4 is a perspective view of the stand with the pad removed;

Fig. 5 is a vertical transverse sectional 45 view on the line 5—5 of Fig. 2.

The stand embodying the present invention comprises a pad supporting member and a filing member and each of the said members is preferably formed from a single 50 length of resilient wire. The pad supporting member comprises resilient spaced portions indicated by the numeral 1 formed between their front and rear ends with bends 2 and rearwardly of the bends 2 the portions 1 slightly converge as clearly shown in 55 Fig. 3 of the drawings. Forwardly of the

bends 2 the said portions diverge as indicated at 3, and are connected by a portion 4. Rearwardly of the bends 2 but relatively close thereto the spaced portions 1 of the supporting member are bent, as at 5, to extend upwardly and rearwardly with relation to the plane occupied by the portions forwardly of the bends 2, it being observed by reference to Fig. 2 of the drawings that 60 when the device is in use the portions forwardly of the bends 2 will constitute a substantially horizontal support for the pad and that the portions rearwardly of the bends 5 will constitute an inclined support 70 for the pad.

The filing member of the stand is, as previously stated, formed from a single length of resilient wire and the wire is bent to form spaced portions 6 and a connecting portion 75 7. The portion 7 connects the lower rear ends of the spaced portions 6 and the said portions 6 are inclined upwardly and forwardly as shown in Fig. 4 of the drawings and intersect the portions 1 of the first described member rearwardly of the bends 5 and are pivotally connected therewith, as at 8. At a point substantially above the bends 2, the spaced portions 6 of the filing member are bent on a gradual curve, as at 9, and 80 are then extended vertically downwardly, as at 10. It will be understood that when the pad is to be fitted to the filing member of the stand, the said filing member may be swung upon the pivots 8 so that the extremities of its portions 10 will clear the side portions of the supporting member of the stand whereupon the portions 10 of the said filing member may be inserted through the perforations in the leaves comprising the pad, 85 or if the pad is to be removed, it may be readily slipped from engagement with the said portions 10. As before stated, the wire from which the stand is formed is resilient, and in order that the filing and supporting 90 members may be mutually connected in their proper positions to perform their several functions when the device is in use, the members 10 are slightly sprung inwardly toward each other, or have a tendency to so 95 spring, and each is formed near its lower end with a notch 11 designed to receive the respective spaced portion of the supporting member of the stand, as clearly shown in Fig. 5 of the drawings. It will now be apparent that when the side portions of the 100 supporting member are engaged in the

notches 11 the members will be prevented from relative movement upon the pivots 8. However, when it is desired to apply or remove a pad to or from the filing member the spaced portions of the supporting member near the bends 2 may be sprung inwardly to clear the notches 10 whereupon the members may be swung upon their pivots, or, if the pad is, prior to its removal, located upon the portions 6 of the filing member the lower ends of the portions 10 may be sprung apart and out of engagement with the spaced portions of the supporting member. By reference to Fig. 2 it will be apparent that the stand is so constructed that the lower extremities of the portions 10 will be spaced above the surface of the desk and that in fact there will be no ends or sharp corners or bends presented in such a manner as to mar the finish of the desk.

The leaves comprising the pad are indicated by the numeral 12 and they are arranged between backing leaves, indicated by the numeral 13, which latter leaves are relatively thick and rigid. The leaves 12 are formed with spaced perforations 14 of a diameter greater than the diameter of the wire from which the filing member is formed so that the leaves 30 may be readily transferred from one to the other of the portions 6 and 10 of the said filing member. The leaves 13 are also formed with perforations 15, but unlike the perforations 14, the perforations 15 are of the same diameter as that of the wire from which the filing member is formed so that the walls of the perforations 15 will bind the portions 6 and 10 of the said filing member. Thus not only are the leaves 13 properly held in position upon the portions 6 and 10 of the filing member but, furthermore, it will be apparent by reference to Fig. 5 of the drawings, that the perforations 15 are so spaced as to prevent relative separation 45 of the lower extremities of the portions 10, and consequently, the said portions cannot become disengaged from the spaced portions of the supporting member and the leaves of the pad cannot become lost or disarranged.

50 The leaves 12 comprising the pad are each printed to represent one day in the year and the leaves are chronologically arranged. Thus the leaf shown in Fig. 1 of the drawings has printed upon its face, as indicated 55 at 16, a calendar for the month of January, 1917 and as this pad leaf is the calendar leaf for the fourteenth day of January, the block or space in the calendar 16 occupied by the numeral 14 has a black background 60 and the said numeral 14 appears in white, as indicated at 17, whereas the other day numerals are printed in black upon a white background. In this or any other desired manner the particular day of the month to

which the calendar leaf relates is distinguished from other days in the calendar 16. Above the calendar 16, the leaf has printed upon its said face the numeral 14, as indicated by the numeral 18, this numeral indicating the day of the month to which the 65 said leaf relates and being printed in relatively large and bold type. At one side of the numeral 14 there is printed the month and at the other side the day, in the present instance, respectively, January and Sunday 70. Upon the obverse face of each leaf 12 there are preferably printed lines 19 and columns 20 and 21 and in the columns 20 there are preferably printed the usual working or business hours of a day and in the 75 columns 21 may be written after the hour designations, the number of minutes after the hour at which an appointment, referred to upon the respective memorandum line 19, is to be kept.

Having thus described the invention, what is claimed as new is:

1. In a device of the class described, a member having front and rear pad supporting portions, and a filing member having spaced portions pivotally connected with the rear pad supporting portion of the first-mentioned member and having the terminals of its said portions arranged for locking engagement with the front supporting portion of the said first-mentioned member, the filing member having its rear portion extending below the pad supported member to form a rest for the rear of the device.

2. In a device of the class described, a member having front and rear pad supporting portions, the rear pad supporting portion being inclined upwardly and rearwardly with relation to the plane of the front pad supporting portion, and a filing member having spaced portions intersecting and pivotally connected with the rear pad supporting portion of the first-mentioned member, the said spaced portions of the filing member forwardly beyond the pivot being turned to extend downwardly and being arranged at their lower ends to have locking engagement with the front pad supporting portion of the first-mentioned member, and the said portions rearwardly of the pivot extending downwardly below the pad supported member to form a rest for the rear of the device.

3. In a device of the class described, a member having front and rear pad supporting portions, a filing member pivotally connected with the rear pad supporting portion of the first-mentioned member, and means affording locking engagement between the said filing member and the front pad supporting portion of the first-mentioned member, the filing member rear-

wardly of its pivot being extended below the pad supported member to form a rest for the rear of the device.

4. In a device of the class described, a pad supporting member having a front pad supporting portion substantially horizontally disposed and a rear pad supporting portion inclined upwardly and rearwardly with relation to the first-mentioned portion, the said member being formed from wire and the said portions having spaced sides, and a filing member also formed from resilient wire and having spaced portions intersecting and pivotally connected with the spaced sides of the rear supporting portion of the first-mentioned member, the said spaced portions of the filing member forwardly of the pivot being inclined upwardly and forwardly and thence extended downwardly and at their ends lying beside the spaced side of the front pad supporting portion of the first-mentioned member, the said ends of the last-mentioned portions of the filing member being provided with notches receiving the said spaced sides of the front pad supporting portion of the first-mentioned member, the said spaced portions of the filing member rearwardly of the pivot being extended downwardly to form a rest for the support of the rear of the device.

5. In a device of the class described, a

pad supporting member having spaced side portions and a connecting portion, the connecting portion constituting the base of the said member and the side portions extending rearwardly from the connecting portion in an approximately horizontal plane to provide a rest for a calendar pad and being thence inclined upwardly and rearwardly to provide a second rest located rearwardly of the first-mentioned rest, and a filing member comprising a connecting portion and spaced side portions, the connecting portion of the said filing member constituting the base thereof and being located rearwardly of the connecting portion of the pad supporting member, the side portions of the filing member being inclined upwardly and forwardly from the connecting portion thereof and intersecting the side portions of the pad supporting member at the upwardly and rearwardly inclined parts thereof and being pivotally connected therewith, the said spaced portions of the filing member having their forward parts bent to extend substantially vertically downwardly with their ends normally interlocked with the said side portions of the pad supporting member.

In testimony whereof I affix my signature.

CARL E. LUNDBERG. [L.S.]
